CARD FILING SYSTEM

Sherman S. Karns, Fresno, Calif.

Application June 9, 1949, Serial No. 97,945

4 Claims. (Cl. 211—58)

1

This invention relates to office equipment and more especially to improvements in a card filing system.

An object of the invention is to provide novel improvements in a card filing system wherein a large number of cards may be filed and wherein any of the cards may be quickly and easily located.

Another object of the invention is to provide an improved card filing system wherein a large number of cards may be filed and all of the cards are within easy reach of a filing clerk at a fixed location such as a chair or other seat.

An additional object of the invention is to provide novel improvements in a card filing system and structure which are simple in construction and easy to operate without unduly tiring the clerk or operator.

A further object of the invention is to provide improvements in a card filing system having structural features whereby the system can be adapted to the filing of several different sized cards as are customarily found in general office filing practice.

Other objects and advantages will appear and be brought out more fully in the following specification, reference being had to the accompanying drawings wherein:

Fig. 1 is an elevation view, partly broken away, of a card filing system embodying my invention.

Fig. 2 is a plan view, partly broken away, of the same.

Fig. 3 is an enlarged partial plan view of one of the filing elements of my system.

Fig. 4 is a sectional view taken along the line 4—4 of Fig. 3.

Fig. 5 is an enlarged sectional view taken along the line 5—5 of Fig. 4.

Fig. 6 is a sectional view taken along the line 6—6 of Fig. 5.

Fig. 7 is a sectional view taken along the line 7—7 of Fig. 3.

Fig. 8 is a sectional view taken along the line 8—8 of Fig. 3.

Figs. 9 and 10 are detailed views showing plates for supporting file boxes of different sizes.

Referring more particularly to the drawings I show a card filing system comprising a base 11 which supports a column or pedestal 12 which in turn supports a plurality of spider members 13 suitably secured thereto as by bolts 14. Fig. 1 shows a card filing system having three tiers of card filing boxes, and a spider member 13 is provided for each tier.

2

Each spider member 13 has radial arms 15, the arms having terminal block formations 16 and 17 as shown. A channel member 18 is secured as by screws 19 to the pair of blocks 16, and a channel member 20 is mounted on each channel member 18 by linear roller bearing race 21, channel members 18 and 20 having upper and lower grooves for the balls 22 of race 21. By this construction channels 20 are slidable forwardly and backwardly on channel members 18. A stop element 23 is provided at each end of the channel members 20 and a cooperating fixed stop member 24 is secured on an arm portion 25 of blocks 16. A hollow frame member 27 has parallel L-shaped channel portions 28 by which it is secured to channel members 20 as by screws 29. Frame 27 has a plurality of upstanding bracket portions 30, each of which supports a bearing screw 31 mounting a roller bearing 32.

19 A circular file box supporting frame 33 has a circular channel 34 forming a track for rollers 32, and the frame has a plurality of box supporting arms 35. Each arm 35 has a pair of diverging end portions 36 and abutment portions 37 and 38. The arms are also formed with threaded screw holes 39, 40 and 41.

20 Triangular plates 42, 43 and 44 are adapted to be secured to the arms and have screw holes for mounting on the arms, holes 39 being used for all of the plates, plates 42 and 43 being secured with the additional use of hole 40, while plates 44 are secured with the use of the hole 41. These plates have side edges 45 which terminate adjacent shoulders 37 and 38, the shoulders effecting stops for the rear walls of the file boxes, the ends of which are supported on the plates. Plates 42, 43 and 44 may have downwardly depending flanges 46 forming aprons, and handles 47 may be provided on the aprons as shown.

25 I show a plurality of file boxes 50 of any suitable construction but made preferably of sheet metal, each having front and rear walls 51 and 52 and end walls 53 which have rolled upper edge portions 54 forming handles, these portions having an opening 55 for a stop screw 56 secured adjacent edge 54 of the spacer plates 42, 43 or 44. Thus the file boxes are supported by end walls 53 on the spacer plates with the rear walls 52 positioned adjacent abutments 37 or 38.

30 It will be seen from the foregoing description that supporting arms 35 and the several sized spacer plates provide a supporting structure for file boxes of several different sizes without other structural alterations or adjustments. Fig. 2 shows a medium sized file box 50 supported on

medium sized spacer plates 43, while Figs. 9 and 10 show small and large spacer plates 42 and 44 respectively secured on arms 35 with the edges 45 of the plates terminating respectively adjacent abutments 37 and 38. The file boxes supported by plates 42 will have the same length as file boxes 50 but will be narrower, while the file boxes supported by plates 44 will be shorter but wider.

In Figures 1 and 2 I show a circular cabinet 57 having a bottom 58 secured on pedestal 12, a top 59, a semi-circular side wall 60, and a semi-circular sliding door 61. Pedestal 12 is secured to bottom 58 at a point forward of its center.

Cushion stops 62 are provided on channel members 20 for engagement with the ends of channel members 18, and stop members 63 are also secured on channel members 20 for engaging the ends of ball races 21.

The operation of the invention should be obvious from the foregoing description. The tiers of file boxes are rotatable through 360 degrees by the roller mounting of supporting frame 33 on rollers 32, and any tier can be slid forwardly and outwardly through the open side of cabinet 57 by the mounting of hollow frame member 27 on spider member 13. Thus any tier of file boxes is readily accessible for filing and any box of any tier is easily brought within reach of a file clerk who does not need to move from a position in front of the filing system. By this construction a very large number of cards may be filed for quick reference, the number of such cards reaching a possible total of 20,000, using three tiers, each having six boxes.

A novel feature of my invention is that any file box or any number of file boxes may be removed from any tier without affecting the operation of the rest of the file. Also, a plurality of tiers may be mounted on a shaft and extend from the floor to the eye line to be used as a standard reference file. While I have described my invention with particular reference to card filing, the invention is not limited to cards but will serve for filing folders, addressograph plates, and various types of records.

It will be understood that the foregoing description is illustrative rather than restrictive of my invention and that changes and modifications may be made without departing from the spirit and scope of the subjoined claims.

Having described my invention what I claim is:

1. A card filing system as described, comprising in combination a base, a pedestal on said base, a spider member on said pedestal having portions extending radially therefrom, a horizontal hollow frame member slidably mounted on said spider member, and a file box supporting frame rotatably mounted for rotation about a vertical

axis on said frame member, said frame member and supporting frame each having an opening through which said pedestal extends.

2. A card filing system as described, comprising in combination a base, a pedestal on said base, a plurality of spider members fixed on said pedestal having portions extending radially from said pedestal, a hollow center horizontal frame member slidably mounted on each said spider member for horizontal movement in one direction, and a hollow center file box supporting frame rotatably mounted on each of said frame members.

3. A card filing system as described, comprising in combination a base, a pedestal on said base, a spider member on said pedestal having arms extending radially therefrom, a bearing block at the end of each arm, a hollow frame member slidably mounted on said arm bearing blocks, a plurality of arcuately disposed bearings on said hollow frame member, and a file box supporting frame rotatably mounted for rotation about a vertical axis on said hollow frame member bearings.

25 4. A card filing system as described, comprising in combination a base, a pedestal on said base, a plurality of spider members on said pedestal, each having arms extending radially therefrom, a bearing block at the end of each arm, a hollow frame member for each spider slidably mounted on each of the spider member arm bearing blocks, a plurality of arcuately disposed bearings on each of said hollow frame members, and a file box supporting frame rotatably mounted for rotation about a vertical axis on the bearings of each hollow frame member, said pedestal extending through the openings of the several frame members.
